UNITED STATES PATENT OFFICE.

PERRY E. MACK, OF MILWAUKEE, WISCONSIN, ASSIGNEE, BY MESNE ASSIGNMENTS, TO BRIGGS & STRATTON CORPORATION, OF MILWAUKEE, WISCONSIN, A CORPORATION OF DELAWARE.

GOVERNOR FOR GAS ENGINES.

Application filed October 24, 1921. Serial No. 510,065.

This invention relates to the fly-wheel construction of small stationary gas engines of the type usually employed for driving washing machines and other light machinery, and particularly to the utilization of the fly-wheel as a means for constituting a part of the governor for controlling the speed of the gas engine and as a blower fan for creating a current of air for cooling the engine cylinder.

Another object of the invention is to simplify the construction of the parts to reduce the cost of manufacture.

With the above and other objects in view, the invention consists in the gas engine governor and blower as herein claimed and all equivalents.

Referring to the accompanying drawings, in which like characters of reference indicate the same parts in different views,

Figure 1 is a plan view of a gas engine with the fly-wheel sectioned and constructed in accordance with this invention;

Figure 2 is a side elevation thereof with the fly-wheel again sectioned;

Figure 3 is a detail view showing the spring and governor arm connections of the throttle stem, and

Figure 4 is a perspective view of one of the governor weights.

In these drawings, 10 indicates a gas engine crank-case mounted on a base 11, constituting the fuel reservoir and supporting the engine cylinder 12, which, instead of being water-jacketed, is provided with projecting fins or ribs 13, which are inclined in the same direction so as to be in line with a current of air created by the blower action of one of the fly-wheels 14.

This fly-wheel is keyed on the crank-shaft 15 and is overhung to bring the weight of its rim near the vertical plane of the bearing for the crank-shaft in the crank-case. Incidentally this overhanging feature of the fly-wheel is utilized to constitute a housing of the hollow interior for containing the governor parts and the blades of the blower fan. Extending inwardly from the rim of the fly-wheel and preferably integrally formed therewith are radial blower blades 16, which, by reason of the rapid rotation of the fly-wheel, tend to create a fan action, causing a current of air to flow from the center of the wheel outwardly. This action

is restrained to some extent by a stationary air deflector 17 consisting of a sheet-metal plate secured to spacing lugs on the crank-case and fitting within the annular flange around the face of the fly-wheel. Air is free to enter through the central opening 18 of the air deflector, but its outlet is confined to the single opening 19 at the edge of the deflector, which is so positioned as to direct the current of air against the cylinder and in line with the ribs 13.

Bent strips of metal form governor weights 19, which are carried within the fly-wheel on headed pins 20. These pins may be threaded in the fly-wheel, but are preferably given a driving fit which is sufficient for the purpose. These weights fulcrum at their bends, where they bear against the face of the hub of the fly-wheel and are capable of swinging from the full line position to the dotted line position of Figure 1 under centrifugal force when the engine is running at speed, the openings 21 in the weights through which the headed pins 20 pass being of such shape as to freely permit of this movement.

The inner ends of the governor weights bear against a washer 22, which is loosely mounted on the crank-shaft but is compelled to turn therewith by reason of notches in its edges engaging the innermost headed pins 20. A spool 23, preferably of hard-wood, is also loosely mounted on the crank-shaft and bears against the disk 22, but does not rotate, as will later be understood. It is provided with a pair of headed pins 24 passing through openings in the forked ends of a governor arm 25. This forked governor arm fulcrums on a projection 26 bent therefrom at the crotch of its fork and bearing on the end of the crank-case bearing. The governor arm is held in place by a headed pin 27 on the crank-case passing through an opening thereof.

A throttle-valve 28 in the intake pipe 29 between the carburetor 30 and the cylinder-head has a projecting stem 31, on which is fixed a U-shaped sheet metal throttle-arm 32, one end of which is connected by a link 33 with the end of governor-arm 25 and the other end to a spring 34 on an adjustable clip 35. The spring thus tends to close the throttle and to swing the governor-arm so as to press its rounded forked ends against

the spool 23 and hold the governor weights in the full-line position, as shown in Figure 1. However, the swinging of the governor weights toward their dotted line position as the engine acquires speed, serves to force the spool against the forked ends of the governor-arm, and, by rocking said arm on its fulcrum, the throttle is moved toward its closed position against the action of the spring.

It will be seen that, by means of this invention, the hollow fly-wheel is utilized as a blower for cooling the engine cylinder and as a governor for controlling the speed of the engine and that the structure has been simplified to make it inexpensive to manufacture.

What I claim as new and desire to secure by Letters Patent is:

29. 1. In a governor, a shaft, a fly-wheel fixed thereon, a collar loose on the shaft and urged toward the fly-wheel with pressure, angularly bent arms with their ends confined between the collar and the fly-wheel and pressed against the face of the fly-wheel by the pressure of the collar, projections on the face of the fly-wheel parallel with the axis of the shaft, there being openings in the arms loosely receiving the projections to be guided thereby, and means controlled by the movements of the collar caused by the rocking of the arms on the face of the fly-wheel.
35. 2. In a governor, a shaft, a fly-wheel fixed thereon, a collar loosely mounted on the shaft and urged toward the fly-wheel with pressure, angularly bent arms with their ends clamped between the collar and the face of the fly-wheel and held in direct bearing against the face of the fly-wheel by the pressure of the collar, said arms being capable of having a rocking movement on the rounded surface of their bent portions against the face of the fly-wheel, means for holding the arms in place, and means dependent on the movements of the collar caused by the swinging of the arms.
40. 3. In a governor, a shaft, a fly-wheel fixed thereon and having a flat face, a collar loosely mounted on the shaft and urged toward the fly-wheel with pressure, angu-

larly bent arms with their ends confined between the face of the fly-wheel and the collar and pressed in direct bearing contact with the face of the fly-wheel by the pressure of the collar, said arms being capable of rocking on the rounded surface of their bent portions against the flat face of the fly-wheel under the action of centrifugal force and so causing the collar to slide on the shaft, there being openings through the arms, pins projecting from the flat face of the fly-wheel and loosely passing through the openings to guide the arms without interfering with their rocking motion, and means operated by the sliding movement of the collar.

4. In a gas engine governor, a fly-wheel mounted on the engine shaft, pins projecting from the face of the fly-wheel, bent 70 governor weights bearing on the face of the fly-wheel and mounted on said pins, a washer loosely mounted on the engine shaft and bearing on the inner ends of the governor weights, a collar loosely mounted on 75 the engine shaft and bearing on the washer, pins on the collar, a forked governor-arm having a bent out projection bearing on the engine shaft bearing to serve as a fulcrum and having its forked ends engaged with the 80 pins of the collar, a pin on the crank-case for holding the governor-arm in place, and a spring-retracted throttle connected with the governor-arm.

5. In a governor, a shaft, a fly-wheel fixed 85 thereon, a collar loose on the shaft and urged toward the fly-wheel with pressure, pins projecting from the face of the fly-wheel, a washer loosely mounted on the shaft and having the collar bear thereon, said washer 90 engaging the pins to turn with the fly-wheel, angularly bent arms with their ends confined between the washer and the fly-wheel and pressed against the face of the fly-wheel by the pressure of the collar, said arms having 95 openings receiving the said pins, and means controlled by the movements of the collar caused by the rocking of the arms on the face of the fly-wheel.

In testimony whereof I affix my signature.

PERRY E. MACK.
